STAMPED METAL WHEEL

J Harold Hunt, Lansing, Mich., assignor to Motor Wheel Corporation, Lansing, Mich., a corporation of Michigan

Application August 16, 1934, Serial No. 740,064

4 Claims. (Cl. 301—9)

The present invention relates to stamped metal wheels of the spoke type, and is a continuation in part of my copending application Serial No. 676,492, filed June 19, 1933, which matured into 5 Patent 2,092,975, September 14, 1937.

The principal object of the invention is the provision of means for strengthening wheels of the type referred to against torsional and lateral strains. This object is obtained primarily by 10 forming the wheel with an integral rim supporting annulus at the outer extremities of the spokes. The particular formation of the spokes themselves is also of importance in this connection. Preferably the spokes are of channel shape 15 in cross section but of decreasing axial depth radially outward, terminating in a substantially flat radially extending peripheral band portion.

Illustrative examples of the invention are shown in the accompanying drawing, wherein:

20 Figure I is a partial side view in elevation of a stamped metal wheel;

Figure II is a sectional view taken on substantially the line II—II of Figure I;

25 Figure III is a section through a spoke taken on line III—III of Figure I;

Figure IV is a section similar to that shown in Figure II but of a slightly modified form of construction; and

30 Figure V is a section through a spoke of Figure IV.

The wheel illustrated in Figures I, II and III comprises a one piece stamped metal body 10 and a rim 11. The wheel body 10 includes a rim attaching zone 12, a wheel attaching zone 13 and 35 an intermediate zone 14.

The wheel attaching zone consists of a disk-like attaching flange 15 provided with a large central opening 16 surrounded by a plurality of smaller openings 17. When the wheel is mounted 40 on a hub, the hub extends through the opening 16 and the wheel is attached to the hub by means of securing studs or cap screws, not shown, which extend through the openings 17.

The intermediate zone 14 consists of a deeply 45 dished conical nave 18, spokes 19, and an axially extending annulus 20 connecting the nave to the wheel attaching flange 15. The nave extends radially outwardly and axially inwardly from the annulus 20. The spokes 19 are of channel shape 50 in cross section, as shown in Figure III, and have roots pressed from the nave 18. The roots are of gradually increasing axial depth radially outward and the spokes which extend therebeyond are of gradually decreasing axial depth radially outward.

The front and side walls of the spokes are flared as clearly shown in Figures I and II. The front walls of the spokes more nearly approach a radial plane than does the nave 18. That is to say, the nave is inclined axially to a considerably greater extent than the front walls of the spokes. This 5 makes for greater resistance to lateral thrusts.

The rim attaching zone 12 comprises an L-shaped annulus 21 having a radially extending outer portion and an axially extending portion 10 forming a rim seat. The radially extending portion of annulus 21 constitutes a peripheral band about the outer ends of the spokes which forms a smooth continuation of the front walls of the spokes. Between the spokes the peripheral band 15 is bent axially inwardly so that the spokes in effect have roots pressed from the band. These roots, as shown in Figure II, are of rapidly increasing axial depth radially inward.

The inner edges of the side walls of spokes 19 20 lie in substantially the same plane as the radially extending peripheral band portion of annulus 21. The channel formation of the spokes is of gradually decreasing axial depth radially outward so that they form a smooth continuation of the substantially flat peripheral band. 25

The construction illustrated in Figures IV and V is substantially identical to that shown in Figures I, II and III, except in the former the radially extending portion of the L-shaped rim attaching annulus is flatter and of greater radial extent; the spokes are of slightly different cross section; the front walls of the spokes are concave instead of convex; the inner edges of the side walls of the spokes lie in a plane spaced axially 30 inwardly from the plane of the peripheral band; and the annulus 20 is of greater radial extent. 35

In both forms of construction the rim 11 is 40 preferably attached to the annulus 21 by means of rivets 22. Likewise, in both forms of construction the rim attaching annulus being integral with the spokes at their outer extremities materially strengthens the wheel structure against torsional and lateral strains.

It will be understood that the present invention is not limited to the illustrated examples shown and described herein but is coextensive with the scope of the appended claims. 45

I claim:

1. A one piece sheet metal wheel body adapted 50 to carry the entire wheel load between the rim and the hub, said wheel body consisting of a single stamping including a radially extending bolting on flange, a generally axially extending annular portion projecting from the periphery 55

of the bolting on flange, a disk portion projecting radially outwardly from said annular portion and having a continuous peripheral flange, said disk portion having an annular series of axially 5 extending depressions with a hole formed in the axially innermost portion of each depression, each of said depressions being of gradually increasing axial depth inwardly throughout the radial extent whereby radially extending ribs are formed between the holes which have an axial 10 extent at the radially inner end at least twice as great as the axial extent at their radially outer end.

2. A one piece sheet metal wheel body adapted 15 to carry the entire wheel load between the rim and the hub, said wheel body consisting of a single stamping including a radially extending bolting on flange, a generally axially extending annular portion projecting from the periphery of the bolting on flange, a disk portion projecting 20 radially outwardly from said annular portion and having a continuous peripheral flange, said disk portion constituting substantially the radial outer half of the wheel body, said disk portion having an annular series of axial extending 25 depressions with a hole formed in the axially innermost portion of each depression, the radial extent of the holes being substantially one-half the radial extent of the disk portion, each of said 30 depressions being of gradually increasing axial depth inwardly throughout their radial extent whereby radially extending ribs are formed between the holes which are of substantially greater axial extent at their radially inner extremities 35 than at their radially outer extremities.

3. A one piece sheet metal wheel body adapted to carry the entire wheel load between the rim

and the hub, said wheel body consisting of a single stamping including a radially extending bolting on flange, a generally axially extending annular portion projecting from the periphery of the bolting on flange, a disk portion projecting 5 radially outwardly from said annular portion and having a continuous peripheral flange, said disk portion constituting substantially the radial outer half of the wheel body, said disk portion having an annular series of axially extending 10 depressions with a hole formed in the axially innermost portion of each depression, the radial extent of the holes being substantially one-half the radial extent of the disk portion, each of said 15 depressions being of gradually increasing axial depth inwardly throughout the radial extent whereby radially extending ribs are formed between the holes which have an axial extent at the radially inner end at least twice as great as the axial extent at their radially outer end. 20

4. In a vehicle wheel of the character described, comprising a tire carrying rim and a supporting web structure therefor fixedly secured to the inner surface thereof and adapted to be removably secured to a hub, the improvement comprising a web structure having a metallic annulus the intermediate portion of which is bulged axially outward forming a convex surface, a plurality of circumferentially spaced openings formed in the radially outward portion 30 of said convex surface, and portions of said annulus adjacent the radially inward margins of said openings which are depressed axially inward, whereby the edges of said openings are substantially in a plane normal to the axle of the 35 wheel.

J HAROLD HUNT.
